CLAIM

The ornamental design for a promotional display with art accents attachable to a vehicle sun visor, as shown and described.

DESCRIPTION

FIG. 1 is a top frontal view of a promotional display with art accents attachable to vehicle sun visor, showing our new design in a closed position of use;

FIG. 2 is a top rear view thereof;

FIG. 3 is a top plan view thereof, showing the display in an open position of use;

FIG. 4 is a bottom plan view thereof;

FIG. 5 is a right side elevational view of the display of FIG. 1, the opposite side elevational view being a mirror image thereof; and,

FIG. 6 is a bottom plan view of the display thereof.

The dash-dot-dash lines in the drawings are for illustrative purposes only and form no part of the claimed design.
